UNITED STATES PATENT OFFICE.

STANLEY H. KNIGHT, OF CHICAGO, ILLINOIS.

SODA-FOUNTAIN.

1,202,192.

Specification of Letters Patent. Patented Oct. 24, 1916.

Application filed October 20, 1911. Serial No. 655,718.

To all whom it may concern:

Be it known that I, STANLEY H. KNIGHT, a citizen of the United States, residing at Chicago, in the county of Cook and State of Illinois, have invented a certain new and useful Improvement in Soda-Fountains, of which the following is a specification.

This invention relates to soda fountains and has for its object to provide a new and improved device of this description.

The invention is illustrated in the accompanying drawings, wherein—

Figure 1 is a view of a soda fountain embodying the invention as seen from the operator's side; Fig. 2 is an enlarged sectional view taken on the line 2—2 of Fig. 1; Fig. 3 is an enlarged sectional view taken on the line 3—3 of Fig. 1; Fig. 4 is an enlarged vertical sectional view; Fig. 5 is a sectional view taken on the line 5—5 of Fig. 4; Fig. 6 is a sectional view taken on the line 6—6 of Fig. 5; Fig. 7 is a face view of one of the controlling valve pieces; Fig. 8 is a sectional view taken on the line 8—8 of Fig. 7; Fig. 25 9 is a sectional view taken on the line 9—9 of Fig. 4; Fig. 10 is a sectional view showing the modified construction for the upper end of the piston rod for the syrup jar.

Like parts are indicated by like numerals throughout the several figures.

As illustrated in the accompanying drawings, the soda fountain is provided with the ice cream cabinet 1, having a top 2. The ice cream cabinet is provided with a wall 3 which separates it from the chamber 4 and in which is contained the soda water cooler 5. This cooler is surrounded by any cooling means such as ice or water, the water being cooled by the ice in the ice cream cabinet. A pipe 6 leads from the cooler to the pipe or header 7, which runs along the wall 8 of the chamber 9 containing the syrup jars or receptacles. Any desired number of syrup jars or receptacles may be used. As herein shown the syrup jars 10 are mounted in a suitable frame 11. The syrup jars are removably mounted in this frame, which frame is provided with a front 12 which is preferably an ornamental slab of any desired material. The frame 11 has at a point between its ends a supporting piece 13, (see Fig. 4.) This supporting piece has a rocking connection with a suitable support which in this instance is the wall 3. The supporting piece 13 is provided with a groove 14 and the wall 3 is provided with

a curved face 15 so that the entire frame and the syrup jar therein may be tilted for the purpose of refilling or removing the pump located in the syrup jar. It will be noted that the syrup jars project below the top of the ice cream cabinet. Each frame 11 is provided with a sliding bolt or locking part 16 which engages the top 17 of the syrup jar receptacle. This locking part is controlled by a movable arm the end 18 of which projects through the front of the frame, (see Figs. 3 and 5), so that it can be controlled by the operator. The frame is slotted, shown at 19, so as to permit the proper movement of this arm to release the locking device 16. When the frame is tilted it is stopped by the stop 20, which has a shoulder 21 which engages the part 17. This stop is provided with a spring 22 and a limiting piece 23 which limits the movement due to the spring. The spring normally holds the shoulder 21 in locking position. A suitable faucet 24 is connected with the front of each of the frames of the syrup jars. This faucet is arranged so that two different liquids may be discharged therefrom, these liquids being controlled by a single handle. As herein illustrated this handle is a separable handle having the two sections, 25 and 26. Means are provided for connecting these two sections together so that they will be moved simultaneously and for disconnecting them so that they can be moved separately. As herein shown one of the sections is provided with a connecting piece 27, the end 28 of which projects from the handle section (see Fig. 5.) The other handle section 25, is provided with a receiving opening 29 into which the connecting piece 27 may be pressed when the operator presses his thumb on the end 28. The two sections of the handle will then be connected together and will move simultaneously.

A retracting spring 30 normally moves the connecting piece 27 so that it will be disconnected from the handle 25 when the part 28 is released. The handle section 25 has an arm 31 which is connected with a short shaft 32 (see Fig. 5), the end of which projects from the side of the faucet 24. The shaft 32 is rotatably mounted in the faucet and is provided with a crank 33 which is connected by a lever 34 (see Fig. 4) with one end of the bell crank lever 35 pivoted at the point 35^a, the other end of the lever 35

rests upon the top of the rod 36 which forms the end of the piston rod attached to the piston 37 by means of which the syrup is pumped from the syrup jar. As shown in Fig. 4 the upper end of the rod 36 is provided with an adjustable stop 36^b so that the movement of the piston 37 can be varied by varying the position of this adjustable stop. A spring 38 is associated with this rod and is adapted to normally return the piston and piston rod to their initial position. In the particular construction shown, the syrup jar is provided at the top with a removable cover 39 which has a central hub 40 through which the rod 36 projects, and which engages the adjustable stop 36^b so as to limit the movement of the piston. This cover is provided with an opening 39^a through which the syrup may be inserted. A casing 41 surrounds the spring and is fastened to the hub 40 so as to be held against movement. When the piston rod is moved downwardly the spring is compressed and when the handle 25 is released the spring automatically returns the parts to their initial position. The upward movement of the piston rod is limited by the stop 42 on the rod 36 which engages the hub 40. In the construction shown the rod 36 is removably connected to the rod 36^a which in turn is removably connected with the piston 37. The piston 37 works in a cylinder 43 at the bottom of the syrup jar. This cylinder has admission openings 44 through which the syrup is admitted thereto. A pipe 45 leads from the bottom of the cylinder to the discharge opening of the faucet. Leading up to each faucet is a charged water pipe 46, which is connected with the source of charged water. A portion of each of these pipes 46 is made flexible so that said faucet, removable front and syrup jar may be tipped without disconnecting the faucet from the source of water supply or the source of syrup in order to permit the syrup jar to be easily filled. As shown in Fig. 2, these pipes are connected with the header 7. The pipe 46 enters the back of the faucet, as shown in Figs. 4 and 6, and communicates with a passageway 49, considerably smaller in cross sectional area than the pipe 46 (see Fig. 6.) The passageway 49 extends through the washer 50, which makes a tight fitting contact with the movable valve piece 51. This valve piece is provided with an opening 52 (see Figs. 7 and 8,) which is adapted to register with the end of the passage 49 when the valve piece is moved to its open position. When in this position the passage 49 is connected with the passage 53 in the valve piece 51 so that the charged water may pass therethrough and through the opening 54 in the washer 50 and into the passage 55 and out through the discharge nozzle 56 (see Fig. 5). 65 This discharge nozzle is preferably pro-

vided with a series of small openings so as to divide the charged water into a series of streams. The valve piece 51 is connected by a projection 57 with the shaft 58 to which is connected the arm 59, fastened to the handle piece 26. It will thus be seen that by moving the handle piece 26 the valve piece can be moved to permit the discharge of the charged water. The valve piece 51 is adjusted to and from the washer 50 by means of the adjusting screw 60. The opening 52 in the valve piece is preferably enlarged to accommodate the variation in movement of the valve piece 51 when the throw of the handle piece is varied by adjusting the adjustable stop 36^b. It will be seen that when the movement of this rod 36 is lengthened by moving the stop 36^b nearer the top the handle pieces 25 and 26 will have to be given a greater movement. The enlarged opening 52 prevents this variation in movement from interfering with the proper discharge of the charged water. When it is desired to remove the syrup jar from the frame 11 the rod 61 is rotated through an arc of 90° by means of the handle 62 (see Figs. 4 and 9.) This rod passes through the front portions 63 of the frame carrying the syrup jar and also through the end pieces 64. These end pieces are provided with circular openings 65 which connect with the slots 66 extending from the opening to the end of the end piece. The rods 61 are provided with flattened portions 67 which fit into the hole 65. It will thus be seen that by turning these rods 90° the flat portions will come opposite the slot 66 and the rear portion of the frame carrying the jar can thus be moved backward, the movement being around the pivots 68 near the bottom of the frame. When it is desired to remove the syrup jars or pumps, the entire frame is tipped forward, the rod 61 rotated and the rear part of the frame and the jar moved backward so as to remove the upper end of the pipe 45 from the faucet and remove the syrup jar from under the lever 35. The jar and pump can then be removed from the frame. The apparatus is arranged so that it may be extended. As shown in Fig. 1 the right hand portion of the device is provided with the doors 69 so that it may be used as a cabinet. There may be a similar extension portion on the other end of the device, a part of which is shown in Fig. 1. The doors 69 are preferably arranged so as to be the width of two syrup jars and may be provided with the same supporting and fastening arrangement as the syrup jar, that is, these doors may be provided with grooves 82 (see Fig. 3) in which fit the upper end of the plate 83, there being a rocking action between them, so that the doors can be rocked down like the syrup jars. The doors may be held in place at the top by a sliding 130

bolt or locking bar 16 which engages the top 17. It will be seen that by this arrangement when it is desired to increase the number of syrup jars this increase can be made without 5 any difficulty, it being only necessary to lift out one of the doors and put in two syrup jars, the syrup jars being simply set in position, the parts being held in place by the same mechanism used for holding the doors 10 in place.

In Fig. 10 I have shown a modified construction for the upper end of the piston rod 36^a. In this construction the part 36^a is connected with the auxiliary rods 81 by 15 means of the yoke piece 80. These auxiliary rods pass through holes in the top of the syrup jar and are connected together at the top by the yoke piece 80. The rod 36 is also engaged to the top yoke piece 80 and passes through an opening in the cover of the syrup jar. The casing 41 in Fig. 10 is closed at the bottom and is screw threaded at the upper end which is attached by means of these screw threads to the central hub 40. 20 It will thus be seen that by this construction the spring 30 is entirely sealed against the syrup because none of the syrup can pass into the casing 41 since its lower end is closed.

30 The pipe 46 is provided with a valve 70 by means of which it may be closed and a coupling 71 by means of which the upper part may be disconnected from the lower part. It is, of course, evident that the parts 35 may be varied in form, construction and arrangement and some of the parts may be omitted and others used with parts not herein shown, without departing from the spirit of my invention.

40 The use and operation of my invention are as follows: When the parts are in position and it is desired to draw off a glass of soda or the like, the operator grasps the two handle portions 25 and 26 and presses 45 upon the end 28 so as to move the pin 27 so as to connect the two handle pieces together. He then moves the handle pieces, as shown in dotted lines in Fig. 4. This movement causes the piston 37 to move downwardly 50 so as to force a charge of syrup into the glass through the pipe 45. It also moves the valve piece 51 so as to open the connection to the charged water supply and this charged water is then discharged into 55 the glass. If it is desired to discharge syrup or charged water alone only one of the handle pieces is moved. If it is desired to adjust the amount of syrup used the stop 36^b is adjusted on the rod 36 to the desired 60 point. When it is desired to refill a syrup jar the button 18 is pressed to release the lock 16 and the jar and its frame are tilted about the curved face 15 so as to bring the top of the jar in position to place syrup 65 therein. When it is desired to remove a

syrup jar the jar and frame are tilted forward after first pressing the button 18. The rod 61 is then rotated by means of the handle 62 and the rear portion of the frame and the jar moved backwardly. The jar 70 and pump can then be taken out. When it is desired to move the jar and the entire frame the valve 70 in the pipe 46 is closed and the pipe disconnected by means of the coupling 71, the entire frame being first 75 tilted forward. The frame and jar can then be removed.

I claim:

1. A soda fountain comprising two sources of liquid supply, a faucet, connections leading from said sources of liquid supply to said faucet, a two part handle, one part of which controls one of said connections and the other part of which controls the other connection, the two parts of said 80 handle normally disconnected and in proximity to each other so that both of them can be simultaneously grasped by one hand or each may be separately grasped.

2. A soda fountain comprising two 90 sources of liquid supply, a faucet, connections leading from said sources of liquid supply to said faucet, a two part handle, one part of which controls one of said connections and the other part of which controls the other connection, the two parts of the handle being disconnected so that they may be moved separately to separately control the discharge of said liquids, and means for connecting the two parts of the handle 100 together so that they will move simultaneously.

3. A soda fountain comprising a syrup jar, a pump associated therewith, a faucet, a syrup conducting connection from the pump 105 to the faucet, a handle movably connected with said faucet, a rod by means of which said pump is operated, a crank connected with said handle, a lever connected with said crank and loosely engaging the upper 110 end of said rod so that when the handle is moved the pump will be operated.

4. A soda fountain comprising a syrup jar, a pump associated therewith, a faucet, a syrup conducting connection from the pump 115 to the faucet, a handle movably connected with said faucet, a rod by means of which said pump is operated, a lever connected with said handle and separate from said rod but having an actuating engagement therewith, 120 so that when the handle is moved the pump will be operated and means connected with said rod for adjusting the movement of said rod so as to vary the quantity of syrup discharged by the pump when the handle is 125 moved.

5. A soda fountain comprising a syrup jar, a pump associated therewith, a faucet, a connection from the pump to the faucet, a handle movably connected with said faucet, a 130

- rod by means of which said pump is operated, a connection between said rod and said handle so that when the handle is moved the pump will be operated and means for adjusting the movement of said rod so as to vary the quantity of syrup discharged by the pump when the handle is moved, a source of charged water supply, a connection therefrom to said faucet, a valve controlling said connection and connected with said handle whereby the syrup and charged water are both discharged from the faucet when the handle is moved, and means associated with said valve for compensating for the variation in movement of said handle in adjusting the movement of said rod to vary the quantity of syrup discharged.
6. A soda fountain comprising a syrup jar, a frame therefor, a faucet connected with said frame, a connection between said faucet and a source of water supply and means for tilting said syrup jar faucet and frame to an inclined position so that the syrup may be placed in said jar without interfering with the connection between the faucet and said source of water supply.
7. A soda fountain comprising a removable front, a syrup jar and faucet connected therewith, said faucet connected with said front and a connection from said faucet to a source of charged water.
8. A soda fountain comprising a removable front, a syrup jar and faucet connected with said front, a flexible pipe connecting said faucet to a source of water supply and

a movable locking device for locking said front in position.

9. A soda fountain comprising a series of separately removable syrup jars, separate frames for each of said jars, a faucet connected with each of said frames and means for separately removing said jars and faucets.

10. A soda fountain comprising a syrup jar, a frame supporting the same, a faucet connected with said frame, a pump for said syrup jar and connecting with said faucet, a handle attached to said faucet and connecting with said pump so as to actuate it when moved, means for disconnecting the front portion of the frame from the rear portion thereof so that the jar and pump can be moved away from the faucet.

11. A soda fountain comprising two sources of liquid supply, a faucet, connections leading from said sources of liquid supply to said faucet, a two part handle, one part of which controls one of said connections and the other part of which controls the other connection and a movable device connected with one part of the handle and adapted when manipulated to connect or disconnect the two parts of the handle.

Signed at Chicago, Illinois, this 14th day of October, 1911.
